CLAIM

The ornamental design for a container tracking device as shown and described.

DESCRIPTION

FIG. 1 is a front, left, top perspective view of a container tracking device in accordance with the present invention;

FIG. 2 is a bottom, right perspective view thereof;

FIG. 3 is a front elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines represent portions of the structure that form no part of the claimed design.

The rear/back surface of the structure is flat and devoid of surface ornamentation. The rear/back surface forms no part of the claimed design.

1 Claim, 6 Drawing Sheets
